UNITED STATES PATENT OFFICE.

EPPA H. RYON, OF WALTHAM, MASSACHUSETTS, ASSIGNOR TO CROMPTON & KNOWLES
LOOM WORKS, A CORPORATION OF MASSACHUSETTS.

FILLING-THREAD-CUTTING MECHANISM FOR WEFT-REPLENISHING LOOMS.

1,009,997.

Specification of Letters Patent. Patented Nov. 28, 1911.

Application filed May 10, 1911. Serial No. 626,176.

To all whom it may concern:

Be it known that I, EPPA H. RYON, a citizen of the United States, residing at Waltham, in the county of Middlesex and State of Massachusetts, have invented certain new and useful Improvements in Filling-Thread-Cutting Mechanism for Weft-Replenishing Looms, of which the following is a specification.

10 My invention relates to a filling thread cutting mechanism for weft replenishing looms which have a magazine for superposed bobbins or filling carriers, and transferring mechanism to transfer a bobbin from the magazine into the active shuttle, on the practical or substantial exhaustion of the filling on the bobbin in said shuttle.

15 My filling thread cutting mechanism is adapted to cut the filling thread on the substantially exhausted bobbin, which is to be removed from the active shuttle, and to hold the end of the filling thread, which leads from the cutter to the selvage of the woven fabric.

20 The object of my invention is to provide a filling thread cutting mechanism of improved construction, and adapted to be applied to and used on looms of the class referred to, and connected with and operated through the operation of some parts of the transferring mechanism.

25 My invention consists in certain novel features of construction of my improvements as will be hereinafter fully described.

30 I have only shown in the drawings a detached portion of a loom of the class referred to, with my filling thread cutting mechanism applied thereto, sufficient to enable those skilled in the art to understand the construction and operation thereof.

35 Referring to the drawings:—Figure 1 is an inner end view of a detached portion of a magazine, and the transerrer mechanism, and a sectional view of the breast beam with my improvements in filling thread cutting mechanism combined therewith; the broken lines indicate the operative position of the shuttle feeler. Fig. 2 corresponds to Fig. 1, but shows some of the parts shown in Fig. 1, in a different position, and also shows a sectional view of the lay beam, as it moves toward the breast beam. Fig. 3 is a plan view of some of the parts shown in Fig. 2, looking in the direction of arrow *a*, same

figure. Fig. 4 shows, on an enlarged scale, the thread cutting mechanism shown in Figs. 1 and 2, detached. Fig. 5 is a plan view of the mechanism shown in Fig. 4, looking in the direction of arrow *b*, same figure. Fig. 6 shows some of the parts shown at the left in Fig. 5, detached, and, Fig. 7 is a section, on line 7, 7, Fig. 6, looking in the direction of arrow *c*, same figure.

40 In the accompanying drawings, 1, Fig. 3, is a portion of a loom side or end frame, 2 is the breast beam, and 3 a stand mounted thereon, which forms a support for the magazine 4, (Figs. 1 and 2).

45 5 is the lay beam, 6, Fig. 3, a portion of the stationary shuttle box on the end of the lay, 7 a part of a shuttle, and 8 a part of a bobbin having filling 9 thereon, which leads from the shuttle 7 to the selvage of the woven fabric, not shown.

50 10, Figs. 2 and 3, is the transerrer arm, having its hub 10' mounted on a stud 11 on a stand 3. Extending downwardly from the hub 10' are the forked arms 12, which are adapted to carry, at their lower ends, the dagger or latch, not shown, in the usual way, which is adapted to be engaged by the bumper on the lay, not shown, to operate the transerrer arm 10, to transfer a fresh bobbin from the magazine into the active shuttle.

55 80 A stand 13 of the magazine has a stud 14 at its lower end, see Fig. 3, on which is loosely mounted the hub 15' of an arm 15, which has secured thereto the shuttle feeler 16. A second arm 15'' on the hub 15', has pivotally connected thereto the lower end 90 of an upwardly extending connector 17, which, through the operation of the transerrer mechanism, not shown, on the substantial exhaustion of filling in the active shuttle, moves downwardly the shuttle feeler 95 16, as shown by broken lines in Fig. 1.

60 All of the above mentioned parts except the shuttle feeler 16, may be of any usual and well known construction.

65 I will now describe my improvements in filling thread cutting mechanism. Upon the breast beam 2 is in this instance secured a stand 18, which forms a bearing for a horizontally extending bar 19. The outer portion 19' of the bar 19 is of circular shape, 105 and is guided at its outer end in an opening in a stand 18, at 18'. A helically coiled expansion spring 20 encircles the circular .

portion 19' of the bar 19, and bears at one end against the end 18', and at its other end against the square shaped end on the bar 19, and acts to yieldingly move and hold the bar 19 in its inward position, and toward the lay 5. The stand 18 has a boss 18" on its upper side, which forms a bearing for a horizontally extending shaft 21, which has its other end journaled in a boss 2' on the 10 stand 3, see Fig. 3. The outer end of the shaft 21 has secured thereon a ratchet wheel 22, which is adapted to be engaged and operated by a pawl 23, which has its hub 23' pivotally mounted on a stud on the end of 15 the arm 12, which arm extends downwardly from the hub 10' of the transerrer 10.

On the operation of the transerrer 10, and the downwardly extending arm 12, the pawl 23 thereon will operate the ratchet 20 wheel 22, to revolve the shaft 21 a certain amount. The inner end of the shaft 21 has secured thereon the pulley 24, which is preferably grooved to receive a belt 25, which passes from said pulley 24 around a small 25 pulley 26, loosely mounted in this instance on a bolt 27 secured to an offset arm 19" on the horizontally extending bar 19. The hub 26', see Fig. 6, on the pulley 26, has rigidly connected thereto a circular knife blade 30 or disk 28, which is preferably toothed as shown, and adapted to hold the filling thread to be cut, and to carry it upwardly, in the direction shown by the arrow in Fig. 4, when the pulleys 24 and 26 are revolved, 35 through the operation of the transerrer arm above described. The filling is in this instance carried toward a knife blade 29, to be severed thereby. The knife blade 29 is secured by a screw 30 to the head 19'', and 40 is yieldingly held against the rotary cutter or circular knife 28.

To hold and clamp the end of the filling thread, which passes from the cutter to the selvage of the fabric, I provide an arm 31, 45 Fig. 4, which has its hub pivotally mounted on a bolt 31' on the end 19'' of the bar 19. A spring 32 is secured in this instance upon the edge of the bar 19, by a screw 32', and is forced downwardly by an adjusting screw 50 33, and acts to yieldingly hold downwardly the arm 31. The end of the arm 31 has a boss 31'', see Fig. 5, and a bolt 34 in said boss has loosely mounted thereon a small pulley 35, adapted to guide a belt 36, which 55 passes forwardly and around a similar pulley 37, see Fig. 4, mounted on a stud 38, which is adjustably secured to the bar 19, in this instance through an elongated opening 19' in said bar, see Fig. 7. The end 19'' 60 of the bar 19 is in this instance provided with a projection 19'', see Fig. 4, over which the belts 25 and 36 pass to hold them in contact, and hold the end of the filling thread, which is led in between said belts.

65 The shuttle feeler 16, which, upon the

substantial exhaustion of a bobbin, is operated by the transerrer mechanism, and is moved downwardly from the position shown by full lines in Fig. 1, to the position shown by broken lines in Fig. 1, to feel for and indicate the proper position of the shuttle, is provided in this instance with means, which are adapted to positively carry the filling thread toward the rotary cutter 28. The 70 feeler arm 16, see Figs. 1, 2, and 3, has in this instance an outwardly extending projection 16', carrying a stud 39 at its end, on which is pivotally mounted the hub 40' of a downwardly extending arm 40, see Figs. 1 and 2. The lower end of said arm 40 carries a stud 41, to which is pivotally connected one end of a rod or connector 42; the other end of said connector 42 is pivotally connected to a stud 43, which is adapted to loosely slide in an elongated slot 16'' in the 75 inclined feeler end 16''' of the feeler 16. The stud 43 has loosely mounted thereon a plate 44, which is provided with a stud 45, which also slides loosely in the slot 16''. The slot 16'' is curved or turned upwardly 80 at its end 16'', which causes a quarter turn movement of the plate 44, when said plate is moved toward the front of the loom, as shown in Fig. 2. The plate 44 has its rear end hook shaped at 44', and is adapted to 85 catch the filling thread 9, when the plate is moved forwardly, to carry the filling thread toward the rotary cutter 28. A sliding movement is imparted to the hook plate or lever 44, on the advance of the lay to its 90 front position, through the engagement of the end of the lever 40, or a roll 46 thereon, with an inclined projection 47, which is secured to the rear wall of the stationary shuttle box 6, see Fig. 3. A helically coiled 95 contraction spring 48, has one end connected to a pin 49 on the lever 40, and its other end, connected to a lug 15''' on the arm 15, see Figs. 1 and 2, and acts to move backwardly the arm 40, to its inoperative position shown, 100 by full lines in Fig. 1.

It will be understood that the details of construction of my improvements may be varied if desired.

Having thus described my invention, what 115 I claim as new and desire to secure by Letters Patent is:—

1. In a filling thread cutting mechanism for weft replenishing looms, a rotatable disk having a series of cutting surfaces to 120 coöperate with a yielding cutter blade, and automatic means to rotate said disk, to carry the filling thread to said cutter blade, to cut the same when a change of filling takes place.

2. In a filling thread cutting mechanism for weft replenishing looms, a rotatable cutter, a stationary cutter to coöperate with the rotatable cutter to sever the filling thread, means to hold one end of said severed 130

- thread, said means comprising two coöperating endless belts, and means to operate the same.
3. In a filling thread cutting mechanism for weft replenishing looms, a disk having a cutting surface thereon, a stationary blade or cutter coöperating therewith, a spool or sheave connected to said disk, an endless belt passing around said spool or sheave, a second sheave over which said belt passes, and automatic means to rotate said second sheave, for the purpose stated, said means including the transerrer mechanism of the magazine for the filled bobbins.
- 10 4. In a filling thread cutting mechanism for weft replenishing looms, a cutter to sever the filling of a practically exhausted carrier, and means to hold one end of the severed filling, said means comprising two coöperating endless belts, and automatic means for operating said belts.

5. In a filling thread cutting mechanism for weft replenishing looms, a cutter, operative, on the ejection of a substantially exhausted filling carrier, to sever the filling on said carrier between the shuttle and the cloth, means to hold one end of said filling, and automatic means to carry said filling into position to be cut by said cutter.

6. In a filling thread cutting mechanism for weft replenishing looms, a shuttle feeler having a cam groove therein, a hook, guided in said cam groove, to catch the filling thread in the running shuttle and carry the same into position to be cut by a cutter, and said cutter, and means actuated by the lay to operate said hook.
